UNITED STATES PATENT OFFICE.

ROBERT BUSTIN, OF ST. JOHN, CANADA.

IMPROVEMENT IN FIRE-ESCAPES.

Specification forming part of Letters Patent No. 151,007, dated May 19, 1874; application filed March 31, 1874.

To all whom it may concern:

Be it known that I, ROBERT BUSTIN, of the city of St. John, of the Province of New Brunswick, of the Dominion of Canada, have invented a new and useful Improvement in Fire-Escapes; and do hereby declare the same to be fully described in the following specification and represented in the accompanying drawings, of which—

Figure 1 exhibits the method of using my invention, Fig. 2 being a perspective view of it as combined with a waist-belt.

In such drawings, *a* denotes a snap-hook joined to a pulley, *c*, by a leather band or connection, *b*. From the said pulley an arm, *k*, extends downward, and at its lower part is provided with an eye, *l*. There is fixed to the arm at its middle, or thereabout, a belaying pin or cleat, *d*, all being constructed and arranged substantially as shown in Fig. 2. To the eye *l* a waist-strap, *h*, is to be suspended, as shown, when the apparatus is in use, the devices represented in Fig. 2 for such purpose being two snap-hooks, *a*¹ *a*², and a connecting-rope, *e*, the lower snap-hook being provided with a swivel, *f*. A swivel snap-hook suspended from the eye *l* will generally answer the purpose as well as the two hooks *a*¹, *a*², and rope *e*.

In Fig. 1 the rope *e* is fastened at or near its middle to the eye-bolt *i* inserted in the window-frame. The upper half of the rope is

shown as being led to and tied to a lamp-post. The snap-hook *a* runs upon this part of the rope, the lower half of the rope being run through the pulley and belayed around the cleat *d*, and held by the person while in the act of descending.

In Fig. 2 two ropes, *e* *e'*, are shown as provided with snap-hooks at their upper ends, they being used with the apparatus, as shown in said figure, and substituted for the single rope *e*, used as represented in Fig. 2.

By means of the auxiliary rope *e* connected with the lamp-post, or any other proper object situated at a distance from the building the descent of the person while escaping from the building on fire will not be in or about in a vertical line and close to the building, but in a course inclined to the horizon, so as to carry him away from the building.

I claim as my invention—

The snap-hook *a*, pulley *c*, arm *k*, cleat *d*, and eye *l*, arranged and combined substantially in the manner as described, and for use with ropes and a waistband or belt, as set forth, the whole constituting a fire-escape, or means of enabling a person to descend to the ground from the window or other part of a building.

ROBT. BUSTIN.
